TEST PLUG FOR OIL CRACKING STILLS

Thomas M. Berry, Jackson Heights, N. Y., assignor to Socony-Vacuum Oil Company, Incorporated, New York, N. Y., a corporation of New York

Application December 14, 1935, Serial No. 54,395

4 Claims. (Cl. 138—90)

This invention is directed to the art of blanking off portions of high pressure tubular oil heaters undergoing test or repairs and has for its object the provision of blanking means which are relatively simple, fully capable of sealing under any desired pressure, capable of being inserted in a minimum of time, and of a nature such that on even the largest stills, they may be inserted with a minimum of labor.

10 Tubular oil heaters designed for high pressure make use of tubes having an internal diameter of three or four inches, in the usual sizes. The pressure and temperature of operation may frequently be of the nature of 1000° F. and 1000 pounds per square inch. Cold test pressures must obviously be in excess of this level. Fittings for return bends, headers and elbows are large forgings and quite heavy. The tubes are normally secured into these forgings by rolling. Individual 20 parts of the box-fitting forgings are heavy and economical operation requires a minimum dismantling of such parts for the insertion of blanking devices for test purposes. Speed in such operation is likewise essential, since time lost to such operations is unproductive and on large 25 equipment unproductive time may be a major factor of operating cost. So far as I am aware, the best type of blanking device formerly available is one of heavy and complicated nature, normally requiring the services of about six trained 30 men for a period of five hours or more to install. I have provided a more competent and simpler form of blanking or test device which may be installed in a few minutes, and even in the heaviest 35 sizes used on stills with the largest tubes, requires the services of only one or two men.

On stills of the type indicated, practically all fittings are of the box type for elbows, crossovers, and the like, and for "frictionless" return bends 40 take the form in which a box is secured to the pipe and a return bend is fitted thereto and held by the box. In all of these fittings, the movable portions of the device such as plugs, return bends, and the like, are held in place by pressure 45 set-screws operating through a lock-block which in turn is secured to the fitting box by lugs co-operating with lugs or slotted extensions on the fitting box. I have taken advantage of this feature in devising my test blank.

50 In order that my invention may be understood, reference is made to the drawing which is attached to and made a part of this specification. In this drawing, Figure 1 shows my novel test blank device, applied to a box fitting of an ordi-

nary type, and Figure 2 shows a half side elevation of the fitting.

For greater clarity, the fitting alone will be explained first. Similar numbers are used for similar parts in both figures. The particular fitting shown here is a "box elbow" comprising a casting 3 into which tubes 4 and 5 are expanded. In the opening 6 the normal closure assembly used in this fitting is shown, consisting of a tapered plug 7 which fits the taper of the opening 10 10. This plug is kept in proper register by a key 8 which cooperates with a peg 9 on the body of casting 6. The casting 6 is extended outwardly to form a sleeve 10, a portion of which is cut away at 11. At several points upon the inside of sleeve 15 15, (four in this case), there are provided lugs 12, having a plane surface toward plug 7. A locking block 13 is provided, on which are lugs 14, which may be placed so as to bear against lugs 12 on sleeve 10. Centrally of lock block 13 20 there is provided a set-screw 15, the end of which may be registered in a depression 16 on the rear of the plug 7. When the lugs on the lock-block and sleeve are engaged and the set-screw 15 tightened, the plug 7 is firmly held in place. 25 Other forms of lock-block and sleeve are common, such as a slotted sleeve, into the slots of which the lugs of the lock-block may pass, and the like. In most "frictionless" fittings, the elbow or return bend is held in place by similar 30 lock-blocks and set screws cooperating with an upstanding sleeve which is affixed to the tubes. All of these fittings of this type which make use of a lock-block and set-screw are capable of using my novel test blank, the variations necessary 35 being only those which may be made by any skilled mechanic.

My improved test blank as shown in Figure 1 is composed of a head 17, to which a disc of lead or other soft metal 18, is secured by a hard metal 40 disc 19 and several bolts 20. On the back of the head 17 is a socket 21, the internal portion of which is of sufficiently great diameter, having a spherical bottom, so that stem 22 may fit loosely therein, and the spherical end of the stem 22, 45 together with the loose fit will enable proper functioning without perfect alignment. The out-board portion of stem 22 is provided with threads 23 of proper design to fit a lock-block 13, and the end of stem 22 carries a wrench square or 50 nut 24. To blank off tube 4, the lock-block and plug are removed from hole 30 opposite tube 4, lock-block 13 and stem 22 are assembled, head 17 is placed on stem 22, the lugs of 13 are placed in register with the lugs on 10, and the whole is 55

drawn tight, the contact of the tube end and soft metal disc 18 forming a perfect seal competent to withstand any desired cold test pressure or steaming or other cleaning operation desired.

- 5 5. To permit of the introduction or withdrawal of cold test fluid, steam, and the like to the blanked off tubes a modified form of my test blank fitting may be used, in which stem 22 is provided with a central passage 25, and wrench square 10 24 is threaded at 26 so a pipe 27 may be inserted, on which may be mounted suitable fittings for the purpose intended, as, for instance, the angle valve etc., shown at 28. In this case, head 17 is provided with passage 29 as shown in dotted lines.
- 15 15. The contact of the spherical surfaces in socket 21 will provide a leak-proof joint at that point under the pressures used, and cold test liquid or steam may be introduced to or withdrawn from tube 4 through the passage thus provided.
- 20 20. Other modifications of this device will present themselves to the skilled mechanic, and I consider these within the scope of my invention, as limited and defined in the following claims.

I claim:

- 25 25. 1. A test blank device for use with a high pressure still fitting making use of a lock-block and set-screw which comprises an elongated threaded shaft to replace said set-screw and cooperate with said lock-block, a blanking disc comprising a hard

metal head and a softer metal contact surface affixed thereto adapted for sealing contact with the end of the tube to be blanked, and means allowing unaligned contact of shaft and head whereby said head may be forced against the tube by pressure from said shaft, when set up in said lock-block.

2. A device as in claim 1 wherein the shaft and head are provided with a coextensive central passage for the admission of fluid to the blanked 10 tube.

3. A test blank device for use with a high pressure still fitting making use of a lock-block and set-screw which comprises an elongated threaded stem to replace said set-screw and cooperate with 15 said lock-block, a wrench square on the out-board end of said stem, the inboard end of said stem having a spherical shape, a blanking disc comprising a hard metal head, on the rear of said disc a socket to loosely receive said stem, a 20 spherical bottom in said socket, and on the face of said disc a deformable metal contact member adapted to make sealing contact with the end of the tube to be sealed.

4. A device as in claim 3 wherein the stem and blanking disc are provided with a coextensive central passage for the admission of fluid to the blanked off tube.

THOMAS M. BERRY.
